CLAIM

We claim the ornamental design for a crisp emitter, as shown and described.

DESCRIPTION

FIG. 1 is a front perspective view of one embodiment of a crisp emitter of the present disclosure;

FIG. 2 is a front elevational view of the crisp emitter of FIG. 1;

FIG. 3 is a rear elevational view of the crisp emitter of FIG. 1;

FIG. 4 is a first side elevational view of the crisp emitter of FIG. 1;

FIG. 5 is a second side elevational view of the crisp emitter of FIG. 1;

FIG. 6 is a top plan view of the crisp emitter of FIG. 1;

FIG. 7 is a bottom plan view of the crisp emitter of FIG. 1;

FIG. 8 is a front perspective view of another embodiment of a crisp emitter of the present disclosure;

FIG. 9 is a front elevational view of the crisp emitter of FIG. 8;

FIG. 10 is a rear elevational view of the crisp emitter of FIG. 8;

FIG. 11 is a first side elevational view of the crisp emitter of FIG. 8;

FIG. 12 is a second side elevational view of the crisp emitter of FIG. 8;

FIG. 13 is a top plan view of the crisp emitter of FIG. 8; and,

FIG. 14 is a bottom plan view of the crisp emitter of FIG. 8.

The broken lines depict portions of the article that form no part of the claimed design.

(Continued)

Separated portions of the crisp emitter that are connected by a bracket indicate that any portion of the article between the broken lines form no part of the claim design. The brackets form no part of the claimed design.
